UNITED STATES PATENT OFFICE.

WINFIELD E. HINSDALE, OF NEW YORK, N. Y.

BASIN WASTE AND OVERFLOW.

974,146.

Specification of Letters Patent.

Patented Nov. 1, 1910.

Application filed September 20, 1909. Serial No. 518,603.

To all whom it may concern:

Be it known that I, WINFIELD E. HINSDALE, a citizen of the United States, and resident of New York, borough of Manhattan, county and State of New York, have made a new and useful Invention in Basin Wastes and Overflows, of which the following is a specification.

My invention is directed particularly to improvements in what are known in the art as "pop-up" wastes and overflows used in connection with earthenware or porcelain basins or bowls ordinarily constructed of one integral piece of material and in which the overflow and waste openings are formed during the process of making such basins or bowls, and it has for its objects, first, to provide novel controlling appliances for the waste valve which shall be so constructed as to enable the user to locate the valve at any desired height and permit the same to remain wherever left. Second, to provide controlling appliances for the valve which may be readily adjusted and shall be absolutely free from the use of detachable devices, such as screws, for effecting their retention in place or for varying their adjustment. Third, to provide controlling appliances for the valve which can be quickly put in place and quickly detached, when it is desired to examine or repair either the valve or any of the parts of the appliances connected therewith. Fourth, to provide controlling appliances for the valve, the operative parts of which shall all be located in the over-flow passage and secured directly to the basin itself at a point above such passage by a single lock-nut readily accessible at all times.

In existing types of basin wastes for use with earthenware or porcelain lavatory or wash basins it has heretofore been customary to drill a hole in the wall between the over-flow passage and the basin proper through which a screw was inserted into one edge of an over-flow grate and in such manner as to lock such grate in position, the controlling appliances being slidingly secured therein. This method of supporting the parts, however, is open to the objection that it is not always possible to locate the same with exact nicety with relation to each other. Furthermore, the constant jarring effect due to the operation of such fixtures

loosens the screw and, therefore, temporarily deranges the operativeness of the parts, necessitating frequent attention. 55

My invention will be fully understood by referring to the accompanying drawings, in which,

Figure 1 is a transverse sectional view taken through an earthenware or porcelain lavatory or wash-basin constructed in the well known manner in one integral piece and illustrating a well known form of cone-shaped valve at the bottom of the basin and the usual over-flow passage connecting the valve with the back and top of the basin wherein is shown an upwardly inclined over-flow opening, my novel controlling appliances for the valve being shown at the upper right hand side of the basin. Fig. 2 is a detail view, partly in section and partly in elevation, of the valve pull-stem. Fig. 3 is an enlarged sectional view of a guiding sleeve 65 for the valve pull-stem, screw-threaded exteriorly at one end and provided at the other with lugs or ears, its interior structure throughout its length being rectangular in cross section, said view being taken on the line X—X Fig. 4. Fig. 4 is a plan view of Fig. 3 as seen looking therat from the top toward the bottom of the drawings. Fig. 5 is an enlarged plan view of the under-side of the valve which is of well known form. 80 Fig. 6 is a detail plan view of a part of the upper and rear face of the basin and at a point above the over-flow passage, said figure illustrating the notches which permit of the admission of the valve controlling mechanism. Fig. 7 is a transverse sectional view taken through Fig. 2 on the line Y—Y and as seen looking therat from the top toward the bottom of the drawings in the direction of the arrows. 90

Referring now to the drawings in detail for a full and clear understanding of the invention, such as will enable others skilled in the art to construct and use the same, 1 represents a well known form of earthenware 100 or porcelain basin constructed in a well known manner in one integral piece and provided with an upwardly inclined over-flow opening 2 and an over-flow passage 3 connecting the same with the outlet at the bottom of the basin. 105

Referring now to the features embodying my improvement, 4 represents a well known

form of cone-valve provided with the usual seat in the bottom of the basin and having the usual radial arms 5, 5, 5, 5, lock-nut 7 and socket 6, said socket being adapted to receive the end of any of the well known curvilinear arms 8 by which such valves are ordinarily raised and lowered.

11 represents the valve pull-stem which is rectangular in cross section and adapted to slide vertically in a rectangular shaped metallic sleeve 16 the latter being screw-threaded on its outside cylindrical surface at one end and provided at the other end with a plurality of lugs 17, 17 corresponding in number to the number of notches or slots 21, 21 extending through the rear top of the basin (see Fig. 6.)

12 is a leaf spring which is secured at one end directly to the lower end of the pull-stem 11 in the manner shown in Fig. 7, its upper end being adapted, when held under compression, to pass beneath a shoulder 13, a condition which takes place when the stem 11 is forced downward through the rectangular opening 18 in the sleeve 16, the spring 12 acting as a friction device adapted to retain the valve controlling appliances and hence the valve in any desired position.

14 represents a pull-knob which is provided at one end with a screw-thread 15 adapted to secure it to the upper end of the stem 11.

19 represents a nut for locking the sleeve 16 and all of the parts supported thereby firmly in position and 20 is an ornamental escutcheon which is put in place after the parts are assembled.

In assembling the parts the necessary adjustment for the lifting of the cone-shaped valve 4 to the desired height is made by screwing the curvilinear arm 8 into the pull-stem 11 and locking it by a milled lock-nut 10, the lock-nut 19 and escutcheon 20 at this time being loosely located in place under the pull-knob 14, which pull-knob is at this time permanently attached to the pull-stem 11. The fixture is now inserted into the over-flow passage 3, the lugs 17, 17 passing through the notches 21, 21, as shown in Fig. 6, and by a quarter turn brought into locking position under the lower surface of the top of the bowl. The lock-nut 19 and cover escutcheon 20 are then screwed into position, locking the fixture firmly to the basin with the end of the curvilinear arm 8 in the socket 6.

By reason of the elasticity of the spring 12 in its concealed position, as shown in Fig. 1, sufficient friction results between said spring and one of the inner walls of the sleeve 16 to retain the pull-stem 11 at any point wherever it may be left. It will, therefore, be apparent that on lifting the pull-knob 14 the valve 4 will be opened and will remain open until the aforesaid knob be

pushed downward to its lowest position, or will remain in effect in any position wherever it may be left.

I am aware that it is broadly old in the art to manipulate a valve in a lavatory basin or bowl through the agency of vertically disposed valve controlling appliances provided with yielding frictional means which retain the valve in whatever position it may be left, and I make no claim hereinafter to include such a structural device, my invention being limited in this respect to the utilization of locking and controlling devices of this general nature when so constructed as to permit of the adjustment and control of the device wholly from the outside of the bowl and the locking of the same by a single lock-nut located above the surface thereof.

Having thus described my invention what I claim and desire to secure by Letters Patent of the United States is—

1. A controlling appliance for the valve of a lavatory basin, embracing a pull-stem, a surrounding sleeve therefor, and a friction device located between the two, said sleeve being provided with a lock-nut at one end and with one or more lugs at the other end; in combination with a curvilinear valve operating rod secured to the pull-stem and an escutcheon adapted, when in position, to surround said pull-stem above the lock-nut and conceal the latter.

2. A controlling appliance for the valve of a lavatory basin, embracing an adjustable valve rod, a pull-stem, a supporting sleeve therefor, and a yielding friction device between the stem and the sleeve; in combination with a lock-nut at the upper end of the sleeve, and additional locking means at the lower end thereof for securing all the parts directly to the basin top.

3. A controlling appliance for the valve of a lavatory basin, embracing a vertically disposed pull-stem adjustably connected to a valve rod; in combination with a spring and sleeve adapted to slidably hold said pull-stem; together with a plurality of lugs at the lower end of the sleeve and a lock-nut at the upper end thereof adapted to secure the sleeve to the basin top.

4. A lavatory basin constructed in one integral piece having a vertically disposed over-flow passage and an over-flow opening extending through one side of the bowl into said passage; in combination with a valve seated in the bottom of the basin and operatively connected with a valve rod extending upward through the over-flow passage and the top of the basin, and to a pull-stem frictionally and slidably held in a sleeve secured in turn directly in the top of the basin.

5. A controlling appliance for the valve of a lavatory basin, embracing a valve rod,

a pull-stem connected thereto, a sleeve slidably surrounding said stem, a spring between the sleeve and pull-stem, lugs at one end of the sleeve, and a nut at the other 5 adapted to detachably and adjustably secure the parts in the top of the basin.

In testimony whereof I have signed my

name to this specification in the presence of two subscribing witnesses.
